BY *Victor J. Evans*

ATTORNEY

WITNESS:

John Ely.

UNITED STATES PATENT OFFICE.

VICTOR NATALE, OF NEW YORK, N. Y.

ICE-CRUSHER.

1,370,345.

Specification of Letters Patent. Patented Mar. 1, 1921.

Application filed June 18, 1920. Serial No. 390,006.

To all whom it may concern:

Be it known that I, VICTOR NATALE, a citizen of the United States, residing at New York, in the county of New York and State 5 of New York, have invented new and useful Improvements in Ice-Crushers, of which the following is a specification.

This invention relates to devices for crushing ice on city streets and the principal 10 object is to produce such a device which shall be simple in construction and efficient in operation.

To this end the invention consists of certain novel construction and combination of 15 parts, the essential features of which are set forth in the following description and particularly pointed out in the appended claims.

The apparatus is fully illustrated in the 20 accompanying drawing consisting of one sheet, in which:—

Figure 1 is a side elevation of my improved ice-crusher.

Fig. 2 is a perspective view of the crusher 25 block.

Fig. 3 is a detail sectional view of the crusher block.

Like characters of reference refer to like 30 parts in all views.

It often happens that the streets of cities become covered with heavy deposits of snow which settles into hard masses or drifts and often become ice before it is possible to remove it. These hardened drifts and masses 35 of ice are a source of great annoyance and present tremendous obstacles to ready removal. The present invention contemplates the providing of means for rapidly breaking up these drifts and masses so they can be 40 easily handled and removed.

Referring more particularly to the drawings, 1 represents a truck or supporting carriage which may be of any suitable construction, but is preferably in the form of an 45 automobile truck. A motor 2 of any suitable type is mounted on the truck and is connected with a winch 3 and with a bevel gear 4. It is of course understood that suitable clutch mechanism is provided between said 50 motor and said winch and between said motor and said bevel gear so that the said motor may operate either or both at the will of the operator.

A post 5 is secured in an upright position 55 on said truck 1 and about the lower end of

this is a base member 6 in which a derrick is mounted for horizontal rotation. This derrick comprises lower and upper members 7 and 8 which are pivotally connected at 9. The member 7 is pivoted in the base 6 and 60 carries attached to its underside, a bevel gear wheel 10 which meshes with the wheel 4. Pivoted at 9' is an auxiliary leg 11 which is normally folded up into the member 8 but which may be let down at will to form an 65 added standard for said derrick.

Mounted in the free end of the member 8 is a pulley 12 and a line or cable 13 from the winch 3 passes over the pulley 14 on post 5, then over said pulley 12, and thence down 70 to the crusher block 15 as shown in Fig. 1.

As shown in Figs. 2 and 3, the block 15 is formed in the shape of a cross comprising four wings 16 radiating at right angles with each other. Each of these wings is 75 provided on its lower edge with a longitudinal notch or groove 17 in which is seated a shank 18 of a blade portion 19. Bolts 20 secure the blades 19 in place. The cutting edge of the blades 19 is not straight, but as 80 shown, formed with a plurality of scallops or waves 21, which greatly facilitates its cutting action. The front and rear wings 16 are secured to the side wings by angle irons and bolts so that if desired they may be removed; or if desired the front wing may be removed and be replaced by a counter weight to balance the structure. 85

It is obvious that by throwing the motor into gear with the wheel 4, the derrick may 90 be turned to present the block 15 over snow or ice deposits at any side of the truck. When the block is in proper position, the winch is operated by the motor to raise the block and then permit it to drop. As the 95 block may be made very heavy it will quickly and efficiently break up the ice and snow deposits. When the blades 19 are dulled or broken they may be quickly and easily removed and replaced. 100

While I have described what I consider to be the most desirable embodiment of my invention, it is obvious that many of the details may be varied without in any way departing from the spirit of my invention; 105 and I therefore, do not limit myself to the exact details of construction herein set forth nor to anything less than the whole of my invention limited only by the appended claims. 110

Now having described my invention what I claim as new and desire to secure by Letters Patent is:—

1. In a device of the class described, the combination of a derrick, a motor adapted to move said derrick in various directions, a block provided with scallop knives, and a winch operable by said motor and co-operative with said derrick to operate said block 10 as and for the purpose set forth.

2. An ice crushing block comprising a body portion made up of a plurality of

wings right angularly disposed to provide a cross, angular shaped corner strips securing said wings together, each wing being recessed along its lower edge, a blade for each wing, each blade having a reduced portion fitted in said recess, and fastening means for securing the blades to the wings as described. 15

In testimony whereof I have affixed my signature. 20

VICTOR NATALE.
